UNITED STATES PATENT OFFICE.

JOEL BARLOW FESLER, OF NEW YORK, N. Y.

FASTENING DEVICE.

1,190,882.

Specification of Letters Patent. Patented July 11, 1916.

Application filed August 8, 1914. Serial No. 855,743.

To all whom it may concern:

Be it known that I, JOEL B. FESLER, citizen of the United States of America, and resident of Richmond Hill, borough of 5 Queens, county of Queens, city and State of New York, have invented certain new and useful Improvements in Fastening Devices, of which the following is a specification.

10 This invention relates to fastening devices of the general nature of automatic lacing devices, and is applicable to various garments, including skirts, corsets, shoes, gloves, and also to various other articles 15 which are to be held together, or which comprise portions adapted to be drawn together.

My invention consists in the novel construction of the device, as hereinafter described and particularly pointed out in the appended claims.

20 The object of my invention is to improve the construction of lacing or fastening devices such as referred to, and to make the 25 same easy of construction and easy of operation and free from liability to derangement.

I will now proceed to describe my invention with particular reference to the drawings, and will then point out the novel features in claims.

Figure 1 shows an elevation of two pieces of fabric (for example, two sides of a skirt or glove or shoe top or the like) with my 35 improved fastening device applied thereto, and adapted to draw the same together or, at will, to permit the separation thereof. Fig. 2 is a view showing the two edges of the fabric detached, and separated, together with the threading device; all shown in elevation. Fig. 3 shows a transverse section of the threading device on the line $x-x$ of Fig. 2. Fig. 4 shows a transverse section on the line $y-y$ of Fig. 2. Fig. 5 shows an 45 end view of the threading device. Fig. 6 shows a side view of the threading device. Fig. 7 shows, on a larger scale than the previous views, a perspective elevation of one of the eyelets and of a portion of the beaded tape or braid, to which the same is 50 secured. Fig. 8 shows an elevation of an alternative form of threading device. Fig. 9 shows a side view of such alternative form of threading device. Fig. 10 shows a transverse section of such alternative threading 55 device on the line $z-z$ of Fig. 8. Fig. 11 is a view similar to Fig. 1 showing this alternative form of threading device in use. Fig. 12 shows an elevation of a further alternative form of threading device, and Fig. 60 13 is an end view thereof.

My improved fastening device comprises two rows of slotted eyelets, such rows adapted for connection to the edge of the articles or edges to be united or drawn together, the 65 eyelets of one row adapted to fit between the eyelets of the opposite row, with slight clearance for flexibility, and a threading member adapted to engage successively the eyelets of the said two rows, and to draw 70 them together, such threading member provided usually with a flexible uniting device, generally having the form of a flexible cord, which is drawn through the eyelets of the two rows as such threading device successively engages the eyelets of said two rows. 75

Referring first to Figs. 1 to 7 inclusive, numerals 1-1 designate the eyelets of one row, and numerals 2-2 designate the eyelets of the other row, the eyelets of each 80 row being connected at suitably spaced intervals to adjacent edges of the articles to be drawn together. In the construction shown, the rows of eyelets 1 and 2 are connected to strips of tape or braid or similar 85 flexible material 3, themselves connected to the edges of the articles 4 to be drawn together. As indicated particularly in Figs. 4 and 7, the eyelets 1 and 2 are not complete 90 eyelets, but have in their outer faces, slots 95 5 adapted to receive the grooves of the threading device hereinafter described. 6 designates the said threading device, the same comprising an approximately triangular or wedge-shaped member, having converging and intersecting side grooves 7 and 8, adapted to receive the edges 9-9 of the eyelets 1 and 2, and having, outside of those 100 grooves 7 and 8, curved guides 10 and 11, adapted to enter the ends of the eyelets 1 and 2, and merging into a stem 12 to which is attached the connecting member, shown

in this instance as a cord 13. The guides 10 and 11 are intersected, where they merge into the stem 12, by the grooves 7 and 8 respectively.

5 The operation of the device will be obvious from Fig. 1. In connecting the two members 4—4, the threading device 6 is drawn upward (as the parts are shown in that figure); and as such threading device 10 is drawn upward, the guides 10 and 11 enter the eyelets 1 and 2 in succession, the edges 9 of said eyelets entering the grooves 7 and 8; and these eyelets travel along the guides 10 and 11, each eyelet of series 2 15 passing over the stem 12 of the threading device so as to intervene between two eyelets of the series 1 on said stem. The edges 9 of the eyelets pass the crossing of the grooves 7 and 8, just as the flanges of car 20 wheels pass through the grooves of track crossings. As the onward motion of the threading device 6 continues, the eyelets pass over the stem 12 onto the cord 13, which holds the eyelets of the two series 25 together, while permitting free bending of the seam formed by the united eyelets. By a reverse operation, the members 4—4 may be detached one from another, the threading member 6 being drawn downward (by 30 pulling upon the exposed end of the cord 13) the eyelets of the series 1 and 2 traveling over the guides 10 and 11, respectively, and separating.

It will be clear that instead of uniting 35 the members 4—4 from the bottom upward as indicated in Fig. 1, they may be united from the top downward; for the threading device 6 may pass through the eyelets 1 and 2 in either direction, as indicated in Fig. 11. 40 I do not limit myself to any particular means for connecting the eyelets 1 and 2 to the beaded tape 3, but the method of connection illustrated in Figs. 4 and 7 is convenient. In that construction, the tape 3 is 45 woven with a bead edge 14; that is to say, its edge is woven around a central core 15 of cord or the like. Such bead edge fabrics are well known. The eyelets 1 and 2 are provided with claws 16 adapted to span the 50 bead edge 14 and to be clamped tightly around such bead edge. It will be obvious that eyelets such as the eyelets 1, provided with such claws, 16, are readily made and applied by automatic machinery, and that 55 such machinery will space the eyelets at precisely the desired distance upon the braid and will do this with great uniformity. I have been able to make fastening devices, such as shown in Fig. 1, which operate very 60 smoothly indeed, and which provide a very flexible seam; and I have made such fastening devices of a size suitable for shoes and gloves, and have also made them in larger sizes.

In case it is thought desirable to provide external guides for the eyelets 1 and 2, as well as internal guides 10 and 11, I may employ a construction such as shown in Figs. 8—11 inclusive, wherein the threading device, there designated by numeral 6^a, is provided, not only with guide grooves 7 and 8, and the internal guides 10 and 11, but also with guide plates 17 overlapping, but spaced slightly away from, the guides 10 and 11, and having flaring portions 18 at their wider ends to facilitate the passage of the eyelets 1 and 2 into the annular space between such guide plates 17, and the guide ribs 10 and 11. In other respects, the threading device shown in Figs. 8 to 11 inclusive is substantially identical with that shown in Figs. 2 and 3; and the operation is the same in both cases.

In some instances, and as indicated in Fig. 12, the interior guides 10 and 11 may be omitted altogether, exterior guides 17 only being provided, which will guide the eyelets over the point of the stem 12.

In a divisional application filed July 9, 1915, Serial No. 38,911, I have claimed the 90 threading device shown in Figs. 12 and 13, also the combination with such threading device of the plurality of rows of eyelets with which such threading device is adapted to coact. Therefore, such device is not 95 claimed specifically herein.

What I claim is:

1. A fastening device such as described, comprising a plurality of rows of open-sided eyelets adapted to be drawn into approximate registry with the eyelets of one row alternated with the eyelets of the opposite row, in combination with a threading device having a stem adapted to pass through such eyelets, and having two guides diverging from such stem and adapted each to pass through the eyelets of one series.

2. A fastening device such as described, comprising a plurality of rows of open-sided eyelets adapted to be drawn into approximate registry with the eyelets of one row alternated with the eyelets of the opposite row, in combination with a threading device having a stem adapted to pass through such eyelets, and having two guides diverging from such stem and adapted each to pass through the eyelets of one series, and a flexible connecting member secured to such stem and adapted to be drawn there-through by the alternated substantially registering eyelets of the two series.

3. A fastening device such as described, comprising a plurality of rows of open-sided eyelets, the eyelets of each row adapted to be drawn into approximate registry with the eyelets of the opposite row, in combination with a threading device having a stem adapted to pass through such eyelets, and

having two guides diverging from such stem and adapted each to pass through the eyelets of one series, and having also a body portion intermediate such diverging guides, 5 but connected thereto and having grooves adjacent to and parallel with said guides to receive the edges of the eyelets, each such groove crossing the opposite guide in proximity to the point where such guides merge 10 into the stem.

4. A fastening device such as described, comprising a plurality of rows of open-sided eyelets, the eyelets of each row adapted to be drawn into approximate registry with the 15 eyelets of the opposite row, in combination with a threading device having a stem adapted to pass through such eyelets, and having two guides diverging from such stem and adapted each to pass through the eyelets of 20 one series, and having also a body portion intermediate such diverging guides, but connected thereto and having grooves adjacent to and parallel with said guides to receive the edges of the eyelets, each such groove 25 crossing the opposite guide in proximity to the point where such guides merge into the stem, and a flexible connecting member secured to such stem and adapted to be drawn thereby through the alternating substantially 30 registering eyelets of the two series.

5. A fastening device such as described, comprising a plurality of rows of open-sided eyelets adapted to be drawn into approximate registry with the eyelets of one row alternated with the eyelets of the opposite 35 row, in combination with a threading device having a stem adapted to pass through such eyelets, and having two guides diverging from such stem and adapted each to pass 40 through the eyelets of one series, such threading device having also outer guides surrounding and substantially parallel to, but spaced away from, the guides first mentioned, and adapted to receive the eyelets 45 within them and to guide such eyelets exteriorly.

6. A fastening device such as described, comprising a plurality of rows of open-sided eyelets adapted to be drawn into approximate registry with the eyelets of one 50 row alternated with the eyelets of the opposite row, in combination with a threading device having a stem adapted to pass through such eyelets, and having two 55 guides diverging from such stem and adapted each to pass through the eyelets of one series, such threading device having also outer guides surrounding and substantially parallel to, but spaced away 60 from, the guides first mentioned, and adapted to receive the eyelets within them and to guide such eyelets exteriorly, the said exterior guides having outwardly flaring portions at the broader end of the

threading device to facilitate the entry of 65 the eyelets into such exterior guides.

7. A fastening device such as described, comprising two strips of bead-edged fabric, each having secured to it a row of spaced eyelets provided with claws embracing the bead, and thereby secured to said bead-edged fabric, the eyelets of the two strips of fabric adapted to be drawn into approximate registry with the eyelets of one row alternated with the eyelets of the 75 opposite row, in combination with a threading device, having guides adapted to draw the eyelets of the two rows into approximate registry and having a stem adapted to pass through such eyelets when in approximate registry.

8. A fastening device such as described, comprising a plurality of rows of eyelets, flexible connecting means connecting and spacing apart the eyelets of each row, the 85 eyelets of the two rows adapted to be drawn into approximate registry with the eyelets of one row alternated with the eyelets of the opposite row, in combination with a threading device having guide means 90 adapted to draw the eyelets of the two rows into approximate registry, and having a stem adapted to pass through such eyelets when in such approximate registry.

9. A threading device for fastening devices such as described, comprising a wedge-shaped member having a stem at its smaller end, and having at its sides guides diverging from such stem and each adapted 100 to pass through slotted eyelets, such eyelets being adapted to pass over said stem.

10. A threading device for fastening devices such as described, comprising a wedge-shaped member having a stem at its smaller end, and having at its sides guides 105 diverging from such stem and each adapted to pass through slotted eyelets, such eyelets being adapted to pass over said stem, said threading device having also grooves adjacent to and parallel with said guides 110 and adapted to receive edge portions of such eyelets.

11. A threading device for fastening devices such as described, comprising a wedge-shaped member having a stem at its 115 smaller end, and having at its sides guides diverging from such stem and each adapted to pass through slotted eyelets, such eyelets being adapted to pass over said stem, each such groove crossing the opposite 120 guide in proximity to the point where such guides merge into the stem.

12. A threading device for fastening devices such as described, comprising a wedge-shaped member having a stem at its 125 smaller end, and having at its sides guides diverging from such stem and each adapted to pass through slotted eyelets, such eye-

lets being adapted to pass over said stem, such threading device having also outer guides surrounding and substantially parallel to, but spaced away from, the guides first mentioned, and adapted to receive said eyelets within them and to guide such eyelets exteriorly.

In testimony whereof I have signed this specification in the presence of two subscribing witnesses.

JOEL BARLOW FESLER.
